STRUCTURAL SYSTEM

Erik Johan von Heidenstam, Stockholm, Sweden

Application November 24, 1937, Serial No. 176,386
In Sweden November 25, 1936

23 Claims. (Cl. 108—23)

The present invention refers to such building structures, intended particularly for bridge and roof structures, which consist of an arch (or frame) with one or more tie members and with 5 braces arranged between the arch and the tie member. As is well known, arch structures of this kind when suitably formed are distinguished by their great capacity to take up a load evenly distributed over the whole span. It is also known 10 that in unfavorable cases of loading, for instance in cases of snow loading or other loading of the one half of the span, for example, the arch will be subjected to pronounced deformations. The bending moments then produced in the arch will 15 be as a rule be decisive for the dimensioning of the structure.

The invention has for its main object to provide such a structural system with an arch and with a tie member or tie members that if the same, for 20 instance on its having been unloaded, is subjected anywhere to a small or great load, this will immediately cause forces which effectively counteract the deformation of the arch.

Another object of my invention is to provide a 25 brace system cooperating with the arch and the tie member in such a manner that the resulting construction will be very rigid and the bending moments arising in the arch very considerably reduced.

30 With these and other objects in view the invention will be described more closely hereinbelow with reference to the accompanying drawings illustrating embodiments of structures constructed according to the system. In the various 35 figures, the same reference characters have been used to corresponding parts.

Fig. 1 shows an arch having a tie member and a brace system comprising two broken arches of braces, hereinafter called brace polygons, 40 operating with the arch and tie member. Figs. 1a and 1b show details.

Fig. 2 shows a construction similar to that in Fig. 1 but adapted to serve as a bridge.

Fig. 3 shows a construction similar to that in 45 Fig. 2 but having an additional pair of brace polygons.

Fig. 4 shows a modified construction which in addition to the braces has a strut arranged between the arch and the tie member. Figs. 4a 50 to 4d show details of this construction.

Fig. 5 shows a structure similar to that shown in Fig. 4 but is intended as a bridge structure.

Figs. 6 to 14 show structures wherein the arch proper has a concave breaking point, that is a 55 breaking point departing from the usual curva-

ture of the arch and directed towards the tie member. All structures shown in these figures are provided with brace systems according to the invention.

Figs. 15 to 18 show details of the structure 5 shown in Fig. 14.

For the sake of simplicity the major part of the embodiments have been shown schematically in a simple way, only the embodiments shown in Figs. 1, 4 and 14 being illustrated more in detail 10 to serve as examples. It is to be understood, however, that the invention is not limited to the use of any special material for the structures in question or to any special method of connecting 15 the various members.

In Fig. 1 the arch 1 is provided with a tie member broken at point 4 and consisting of two parts 2 and 3. The breaking point 4 is connected with the arch by means of two rows of braces 22 and 23 each consisting of a plurality of braces 22a to 22e and 23a to 23e forming angles with each other. In the following the broken arches of braces thus formed will be called "brace polygons." They are typical tensional members. At 20 their breaking points the brace polygons are secured to secondary braces 11 which in this case form vertical suspension rods. In the example shown these suspension rods do not carry any directly loaded part and for this reason they terminate at the brace polygons 22 and 23. The rods 30 11 may therefore be regarded as pertaining to the tensional members of the system.

Fig. 1a which illustrates the joint at the left end of the arch shows that the arch consists of a broad-flanged rolled girder 1 to which is welded a 35 gusset 7 which, in turn, is welded to the part 2 of the tie member. At the breaking point 4 shown in Fig. 1b the parts 2 and 3 of the tie member as well as the braces 22a and 23a and the suspension rod 11 are connected by means of a gusset 8, preferably also by welding. Since the parts 2, 3, 11, 22 and 23 are all tensile members they 40 may preferably consist of round iron bars. The structure shown in Fig. 1 is primarily intended for halls or the like with a great span.

The camber m of the breaking point, that is to say the level thereof above the connecting line between the ends or bearings of the arch, is determined by the shape of the arch, the 50 span, the rise of the arch, the position of the points of attachment of the braces and by the values of the dead load and the movable load, in a manner such that bending moments produced in the arch will be reduced as far as possible 55

for the most dangerous or commonest cases of loading.

At a load (primary load) applied for instance to the left portion of the arch, this portion will be depressed in the ordinary way with a corresponding bulging of the right portion of the arch. The brace polygon 22 and the secondary braces or suspension rods 11 belonging thereto will thus become unstrained, since they are pure tensile members without any appreciable capacity to take up pressure. The loading of the arch also entails an increased tensile stress in the tie member, and if the brace polygon 22 is unstrained, the tensile stress in the part 2 shall thus be balanced by the tensile stresses in the brace polygon 23, the suspension rods 11 belonging thereto and the part 3. This consequently has the effect that the brace polygon 23 and its suspension rods will load the arch 20 in its right portion, and this load (secondary load), which obviously will be greater the greater the primary load is, tends to counteract the bulging of the arch in the right portion thereof. The system thus acts as a so-called variable 25 system which in this connection chiefly means that when the arch is loaded (primary loading), for instance by means of a movable load on the roadway of a bridge, one or more of the braces will bring about a secondary loading of the arch, which counteracts the deformation of the arch on account of the primary load. By the combination of the broken tie member with the variable system it has thus been brought about that the breaking point 4 may practically be 30 considered as constituting a fixed point, relatively to which the arch is retained, whereby its deformation is reduced. It is obvious also that the back strain obtained through the tensile stress in the brace polygon 23 will be effective 35 already at a small primary load and becomes operative as soon as the arch shows a tendency toward deformation. The system will be very rigid, and by the fact that the bending moments in the arch are appreciably reduced, the latter 40 may be dimensioned considerably lighter than is the case in the hitherto practised systems of anything like a similar appearance.

Fig. 2 shows a development of the system according to Fig. 1 as applied to a bridge. The 50 tensional members 22 and 23 are arranged here in the same manner as in Fig. 1, and are secured to the suspension rods 11, but the latter extend down to and carry the bridge roadway 10. When a movable load is applied to the bridge roadway, 55 the load is transferred by the suspension rods and will cause such conditions of stress in the tensional members 22 and 23 as have been described in connection with Fig. 1.

When applying the construction to bridges 60 where the roadway has a certain dead weight, it is suitable to make the structure so that its dead load causes immaterial moments in the arch only. To achieve this object the brace polygons (compare Fig. 2) should as a rule be 65 subjected to tension when the structure is being erected. If in this case the structure loaded by its dead weight only is subjected, for instance, to a movable load on the left half thereof, this entails that the stress in the left brace polygon 70 will be reduced—or entirely caused to cease—whereas the stress is increased in the right brace polygon. The system will thus be operative in a very favourable way, in that a movable load on the left side, for example, will reduce the load 75 on the left brace polygon loading the arch, but

will increase the load on the right brace polygon loading the arch, or, in other words, the load on the arch is reduced where the arch is normally apt to be pressed inwardly, and is increased where the arch is normally apt to bulge. 5

In the embodiment according to Fig. 1, the brace polygons may also be strained from the beginning, which, in principle, entails the same effect as described in connection with Fig. 2.

What has been stated above with reference 10 to Figs. 1 and 2 regarding the mode of operation of the system also holds true for the embodiment according to Fig. 3, which shows a further development of the system according to Figs. 1 and 2. According to Fig. 3, two broken 15 tensional members 24, 25 and 26, 27, respectively, are provided, which, the same as in the construction just described, form broken arches and are connected to the suspension rods 11 at the points of intersection with these rods. The two 20 pairs of brace polygons are displaced relatively to each other within each pair, so that their top points do not coincide. This system involves the advantage that the system is rendered still more rigid at an unevenly distributed load, which will 25 be conceived in accordance with the above, from the fact that with a onesided, unevenly distributed load, for example, the conditions on the primarily unloaded side will be the same, while the unloading of the brace polygonal system on the primarily loaded side will be most effective 30 within that portion where the load is most heavily concentrated. Here, too, it will be found suitable to have the braces put under tension when they are fixed in their places. The system is 35 particularly suitable for large spans.

As a consequence of the above, the invention also relates to a method in the constructing of structures according to the foregoing, particularly according to Figs. 1, 2 and 3. The method 40 consists substantially in that, after the arch, the tensional members, the tie members and any suspension rods and the roadway have been arranged in their places, the tie members and tensional members are subjected to initial tensile 45 stresses of such magnitude that a suitable stress is imparted to the arch, or the arch is made practically free from moments relative to the deadweight of the structure or to the commonest cases of loading, whereupon the tie and tensional 50 members are definitely secured while this initial stress is maintained. The initial stresses, which thus have the effect described in the foregoing, may be produced in any suitable manner, for instance by means of hydraulic jacks or the like. 55

It has been stated in the foregoing that the braces are constituted by tensional members, and that one or more of such tensional members extend from the breaking point of the tie member. It is feasible, however, also to make the 60 braces mediating the secondary load, or certain of these braces as compressional members. In such a case it may become necessary to make the tie member rigid, for instance by making the same or certain parts thereof as latticeworks. 65

The structural system as described may be applied to 0, 1 and multi-hinged arches of arbitrary form provided with a tie member which is saddle-backed, if desired, and the system is not limited to constructing the arch from a certain 70 material. Thus, the arch may be made as an iron or wooden structure, but the system is also applicable in concrete structures. The system shows great rigidness, that is to say small moments and deformations. This is of great im- 75

portance, particularly in concrete structures, also from the point of view that hereby facilities are provided to cause the cross sections of the arch to be pressed over the whole surface, which entails—in addition to a lessened dead weight and a reduced consumption of material—an increase of the safety against buckling. Through the invention, it will be possible, furthermore, in a number of cases to employ externally statically determined systems to economical advantage, such systems showing constructively good properties, for instance with respect to reactive forces and to temperature and shrinkage stresses.

As will be found from the foregoing description, the expression "variable system" must not be construed as involving that certain braces must under all circumstances be rendered inoperative, that is to say be unstrained, for this is of course a matter which depends on the application and the magnitude of the load. The expression involves that this tendency and possibility of being rendered inoperative is present, although in a certain case of loading the braces are not perhaps unstrained.

Fig. 4 shows an arch 1 with a tie member 2. Extending from the middle point 30 of the arch is a compressional strut 31 to a point 32 at the center of the tie member. This point 32 is connected with the end points 33 and 34 of the arch, respectively, by means of brace polygons 35 and 36, each consisting in the example illustrated of six members. The arch 1 is broken in correspondence to the brace polygons, and arranged between the breaking points of the arch and the breaking points of the polygons are a number of secondary braces 11. Moreover, the end points of the arch are connected with the middle point 30 by means of obliquely directed braces 37 and 38, which between their end points are also connected with the arch by means of compressional braces 39. These compressional braces 39 are preferably disposed in such places where there are breaking points in the arch and the brace polygons, so that these braces may serve both as compressional members between the arch and the oblique braces 37, 38 and as tensional members between the arch and the brace polygons 35 and 36. Examples of this are shown, inter alia, in the two central compressional members 39, which are continued beneath the oblique braces 37 and 38 directly by the tensional members 11. The members 11 and 39 may, for the sake of simplicity, be commonly termed "the vertical braces", although they need not necessarily be vertical. Thus, for instance, the compressional members 39 may be positioned at right angles to the arch section in question.

Fig. 4a shows the joint of the various members at the left end of the arch. Also in this instance, the arch consists of a broad-flanged girder to which the members 2, 35 and 37 are connected by means of a gusset 7. Fig. 4b shows that the braces 37, 38 and the strut 31 are connected to the crown 30 of the arch by means of a gusset 1a. Fig. 4c which is a section taken along the line c—c in Fig. 4b shows that the strut 31 may consist of two U-irons. Fig. 4d shows the connection at the middle point 32 of the tie member by means of a gusset 8.

The structure shown in Fig. 4 is operative in the same manner as described in connection with Figs. 1 to 3 but in addition hereto the members 37 and 38 will come into action as follows.

If the left half of the bridge in the figure is

loaded by means of a movable load while the right half remains unloaded the oblique brace 37 is brought under a tensile stress, whereas the oblique brace 38 slackens or is subjected to compressive stress. From this point of view, the oblique braces 37 and 38 may be made so as to be able also to transfer pressure. The tensile stress in the oblique brace on the primary loaded side corresponds to an increase of the pressure in the arch in the most heavily loaded portion of the arch due to the unevenly distributed load.

If the dead load be disregarded, the structure will thus act theoretically as a variable system as previously described. The structure is well stiffened, the bending moments are materially reduced, and the buckling risk for the loaded portion of the arch is greatly reduced, which is all the case also in regard to the embodiments to be described in the following.

If it is desired to load the tie member, it may be found suitable in the embodiment shown in Fig. 4 to cause the suspension rods 11 or certain ones of the same to extend down to the tie member so as to carry the latter. The tie member may then, for instance, be made as a girder and be employed for the carrying of cross bars, telfer carriages or the like. This is also the case with the embodiments described later on.

The structure shown in Fig. 5 corresponds broadly with that shown in Fig. 4, but is intended as a bridge structure, the bridge roadway 10 being carried by the suspension rods. It is preferable here to make the bridge roadway as a tie member. The structure may also be brought into use, if in place of a bridge roadway it is desired to cause the tie member to carry some other heavier load.

Fig. 6 shows an embodiment, which in regard to the tie member 2, the compressional member 31, the brace polygons 35 and 36 and the braces 11 corresponds to the structure disclosed in Fig. 4. Differing from the latter structure, however, the arch is in the present case broken in a concave manner, that is to say broken inwardly in a direction toward the tie member, the breaking point 40 being connected with the tie member by means of the strut 31. The mode of operation of the structure corresponds in principle to what has been previously described. Through this construction it will be possible also for great one-sided loads to make the arch practically free from moments, and such as to have substantially only to take up normal forces.

In the embodiment shown in Fig. 7, there is again the arch broken in a concave manner, the breaking point of which is connected with the tie member at the point 32 by means of the strut 31. In this case, however, each half of the arch shows two brace polygons 43, 44 and 45, 46, respectively, which at their breaking points are connected to the suspension members 11. Besides, the brace polygons are connected with each other at their points of intersection 47, 48.

All of the embodiments above described may be employed in connection with broken tie members in the manner described in connection with Figs. 1 to 3. Examples of applying the present invention to structures having a broken tie member are illustrated in Figs. 8 and 9.

The structure shown in Fig. 8 thus has an arch 1 broken in a concave manner and brace polygons 35 and 36 of the kind previously described. The tie member 2 is broken, however, as will be seen from the figure, and the strut 31 connects the

breaking point 32 with the breaking point 40 of the arch.

The embodiment according to Fig. 9 corresponds to the structure shown in Fig. 8, with the difference that it is intended as a bridge structure. The bridge roadway 10, which may extend above, below or through the breaking point 32, is carried here by the extended suspension rods 11.

10 The following Figures 10 to 14 show embodiments in which the oblique braces 37, 38 described in connection with Figs. 4 and 5 are employed in arches having a concave breaking point.

15 In Fig. 10 the braces 37 and 38 are broken and connect the ends of the arch with the crown. At their breaking points, these braces are connected with the arch by means of the secondary braces 11. The braces 37 and 38 aid toward stiffening the arch further, and in neutralizing or counter-20 acting the tendency thereof toward lateral displacements from the loaded side. Such a tendency may involve, for instance, that when the left side of the arch in the figure is primarily loaded, the crown 40 tends to move to the right. 25 This is counteracted by the brace 37, which is subjected to tensile stresses and produces a back strain at the point 40 increasing with the load.

30 Fig. 11 shows an embodiment, wherein the braces 37 and 38 are constructed broadly in the same manner as according to the preceding figures. The brace polygons 35 and 36, on the other hand, are at their inner portions, that is to say adjacent to the center of the arch, straight for a greater length and not connected with the arch by means of secondary braces. For the stiffening of the inner portions of the arch, there are arranged combined braces 49 and 50, which are connected with the braces 37 and 38, respectively, as well as with the arch. Otherwise, the arrangement is operative in the same manner as the arrangement according to Fig. 10.

35 In the embodiment according to Fig. 12, the braces 37 and 38 are straight, whereas the brace polygons 35 and 36 are arranged in the same manner as in Fig. 10. Tensile members 51 and 52 extending from the point 32 are connected with the braces 37 and 38, respectively, and also, by means of vertical braces, with the arch to stiffen the inner portions thereof. The dotted lines 53 indicate that the vertical braces may be made as 40 suspension members and carry a bridge roadway or other load on the arch. This possibility is also present in the embodiment shown in the remaining figures.

45 In the embodiment according to Fig. 13, the braces 37 and 38 are also straight. To stiffen the inner portions of the arch, special tensional members 54, 55 are connected with the brace polygons 35 and 36 and with the braces 37 and 38, from the connecting point of which tensional members with the braces 37 and 38, respectively, vertical braces 56, 57 extend to the arch. These braces 56 and 57 are furthermore connected with the polygons 35 and 36 at breaking points 58, 59 50 of the same.

55 In the embodiment according to Fig. 14, the braces 37, 38 are shown as being straight. The brace polygons, on the other hand, are of a construction differing from the embodiments shown 60 in Figs. 10-13, in that there are provided two different brace polygons within each half of the arch, that is to say one, the various members of which are designated by *a*, *b*, *c*, *d*, and a second, the various parts of which are denoted by 65 *e*, *f*, *g*. The member *a* may at the same time

form the outer portion of the brace 37 extending between the end of the arch and the crown 40. The brace polygons are in a manner previously described connected at their breaking points with the arch by means of secondary braces. Now, the two brace polygons *a*-*d* and *e*-*g* are at a point above their common point of intersection 60 connected by means of a bonding brace, i. e. a broken brace 61a, 61b in the case illustrated, the breaking point of which is likewise connected with the arch and with the point of intersection of the brace polygons, besides which the end points of this brace are connected with the arch by means of vertical braces. This bonding brace, which may be straight between its ends located on the brace polygons, makes it possible that the resultant of the brace system on the least loaded side may take a position nearer to the arch than would be the case, if this bonding brace were lacking. The inner end 10 point of the bonding brace 61 is located on the brace 37 connecting the end of the arch with the crown, as will be seen from the figure.

15 With the exception of the strut 31 all members below the arch in Fig. 14 are tensional members although as a tie member there is used a double T-iron. This is for the purpose of letting the tie take up a direct load, such as transversing telfer carriages. For this purpose the vertical braces extend down to and are connected 20 with the tie member.

25 Fig. 15 shows the joint at point 32. To the tie member 2 there is welded a gusset plate 62 which, in turn, is connected with the inner ends 30 *d* and *e* of the brace polygons. Likewise the strut 31 is connected to the gusset 62. As shown the strut is formed by a broad-flanged girder but instead two U-irons may be used. The construction shown in Figs. 14-18 is a roof truss and is an example taken from practice. To secure the different trusses laterally I employ a tube 63 which extends through the several joints 35 40 45 50 55 60 65 70 75 80 85 90 95 100 105 110 115 120 125 130 135 140 145 150 155 160 165 170 proximity of these ends, for instance somewhat higher, so that a portion of the end of the arch may be regarded as the final brace or be considered to serve as such. Moreover, the brace polygons and the tensional members may, instead of extending from the connecting point between the strut and the tie member, extend from this strut somewhat above the point. Finally, the tie members may in all embodiments be elevated, so that the springers will be located beneath the same, that is to say beneath the ends of the arch proper.

What I claim is:

1. In a structural system comprising an arch and a tie member, said tie member being broken in consisting of two parts forming an angle with each other, the point of said angle being directed against the arch, at least two brace polygons, each consisting of a broken arch of braces, provided between the arch and the breaking point of the tie member, and secondary braces connecting the breaking points of said brace polygons with the arch.

2. In a structural system comprising an arch and a tie member, said tie member being broken in consisting of two parts forming an angle with each other, the point of said angle being directed against the arch, at least two brace polygons, each consisting of a broken arch of braces, provided between the arch and the breaking point of the tie member, and secondary braces connecting the breaking points of said brace polygons with the arch, the various parts being so arranged relatively to each other that at primary loading of the arch the braces bring about a secondary loading of the arch counteracting deformation of the arch on account of the primary load.

3. In a structural system comprising an arch and a tie member, at least four brace polygons, each consisting of a broken arch of braces, provided between the arch and the tie member, a plurality of brace polygons being arranged for each half of the span of the arch, the top points of said brace polygons being displaced relatively to each other in the longitudinal direction of the arch and secondary braces connecting the breaking points of said brace polygons with the arch.

4. In a structural system comprising an arch and a tie member, at least two brace polygons, each consisting of a broken arch of braces, provided between the arch and a common point on the tie member, a vertical member forming a strut connecting said common point with the arch and secondary braces connecting the breaking points of said brace polygons with the arch, additional obliquely positioned braces extending from the connecting point of the arch with said strut to the ends of the arch, said additional braces being arranged at an unevenly distributed load on the arch to take up a tensile stress corresponding to the increase of the pressure in the arch in the part thereof subjected to the heaviest load.

5. In a structural system comprising an arch having at least one concave breaking point and at least one tie member, at least two brace polygons, each consisting of a broken arch of braces, provided between the arch and the tie member, secondary braces connecting said brace polygons with the arch, and at least one strut connected with the arch and cooperating with said brace polygons.

6. In a structural system comprising an arch having at least one concave breaking point and at least one tie member, at least two symmetrically arranged brace polygons, each consisting of

a broken arch of braces, provided between the arch and the tie member, secondary braces connecting the breaking points of said brace polygons with the arch, and at least one strut connected with the arch and cooperating with said brace polygons, the various parts being so arranged relatively to each other that at primary loading of the arch the braces bring about a secondary loading of the arch counteracting deformation of the arch on account of the primary load.

7. In a structural system comprising an arch having at least one concave breaking point and at least one tie member, at least two brace polygons, each consisting of a broken arch of braces, provided between the arch and the tie member, secondary braces forming suspension rods and connecting the breaking points of said brace polygons with the arch, and at least one strut connected with the arch and cooperating with said brace polygons.

8. In a structural system comprising an arch having at least one concave breaking point and at least one tie member, at least four brace polygons, each consisting of a broken arch of braces, provided between the arch and the tie member, a plurality of brace polygons being arranged for each half of the span of the arch, the top points of said brace polygons being displaced relatively to each other in the longitudinal direction of the arch, secondary braces connecting said brace polygons with the arch, and at least one strut connected with the arch and cooperating with the tie member and the brace system.

9. In a structural system comprising an arch having at least one concave breaking point and at least one tie member, at least four symmetrically arranged brace polygons, each consisting of a broken arch of braces, provided between the arch and the tie member, a plurality of brace polygons being arranged for each half of the span of the arch, the top points of said brace polygons being displaced relatively to each other in the longitudinal direction of the arch, secondary braces connecting the breaking points of said brace polygons with the arch, and at least one strut connected with the arch and cooperating with the tie member and the brace system, the various parts being so arranged relatively to each other that at primary loading of the arch the braces bring about a secondary loading of the arch counteracting deformation of the arch on account of the primary load.

10. In a structural system comprising an arch having at least one concave breaking point and a tie member, a plurality of brace polygons, each consisting of a broken arch of braces, connected to the arch and to a common point on the tie member, a strut connecting said common point with the arch, and secondary braces connecting said brace polygons with the arch.

11. In a structural system comprising an arch having at least one concave breaking point and a tie member, a plurality of brace polygons, each consisting of a broken arch of braces, connected to the arch and to a common point on the tie member, a strut connecting said common point with the arch, secondary braces connecting said brace polygons with the arch, and additional obliquely positioned braces extending from the connecting point of the arch with said strut to the ends of the arch, said additional braces being arranged at an unevenly distributed load on the arch to take up a tensile stress corresponding to the increase of the pressure in the arch in the part thereof subjected to the heaviest load.

12. In a structural system comprising an arch having at least one concave breaking point and a tie member, said tie member being broken in consisting of two parts forming an angle with each other, the point of said angle being directed against the arch, a plurality of brace polygons, each consisting of a broken arch of braces, provided between the arch and the tie member, secondary braces connecting the breaking points of said brace polygons with the arch, and at least one strut connected with the arch and with the breaking point of the tie member.
13. In a structural system comprising an arch having at least one concave breaking point and a tie member, a plurality of brace polygons, each consisting of a broken arch of braces, provided between the arch and the tie member, a vertical strut connected with the breaking point of the arch and with the tie member, and secondary braces connecting the breaking points of said brace polygons with the arch.
14. In a structural system comprising an arch having at least one concave breaking point and a tie member, a strut connecting the breaking point of the arch with said tie member, and a plurality of braces connecting the arch with the connecting point of said strut with said tie member.
15. In a structural system comprising an arch having at least one concave breaking point and a tie member, a plurality of brace polygons, each consisting of a broken arch of braces, provided between the arch and the tie member, a vertical strut connected with the breaking point of the arch and with the tie member, secondary braces connecting the breaking points of said brace polygons with the arch, at least some of said secondary braces forming suspension rods extending to and connected with the tie member and the tie member being so arranged that it is capable of taking up additional loads in the form of cross bars or the like.
16. In a structural system comprising an arch having a concave breaking point and a tie member, a strut connecting the breaking point of the arch with the tie member, a plurality of brace polygons, each consisting of a broken arch of braces, connecting the arch with the connecting point of said strut with the tie member, secondary braces connecting said brace polygons with the arch, and additional, obliquely positioned braces extending from the connecting point of the arch with said strut to the ends of the arch, said additional braces being arranged at an unevenly distributed load on the arch to take up a tensile stress corresponding to the increase of the pressure in the arch in the part thereof subjected to the heaviest load.
17. In a structural system comprising an arch having a concave breaking point and a tie member, a strut connecting the breaking point of the arch with the tie member, a plurality of brace polygons, each consisting of a broken arch of braces, connecting the arch with the connecting point of said strut with the tie member, secondary braces connecting said brace polygons with the arch, additional, obliquely positioned braces extending from the connecting point of the arch with said strut to the ends of the arch, and further braces extending between the arch and points on said additional braces, between the ends thereof.
18. In a structural system comprising an arch having a concave breaking point and a tie mem- ber, a strut connected to the breaking point of the arch and to said tie member, at least two brace polygons, each consisting of a broken arch of braces, provided between the arch and the tie member in each half of the span of the arch, the top points of said brace polygons being displaced relatively to each other in the longitudinal direction of the arch, a bonding brace connecting said brace polygons at a point above their point of intersection, and secondary braces connecting the breaking points of said brace polygons with the arch.
19. In a structural system comprising an arch having a concave breaking point and a tie member, a strut connected to the breaking point of the arch and to said tie member, at least two brace polygons, each consisting of a broken arch of braces, provided between the arch and the tie member in each half of the span of the arch, the top points of said brace polygons being displaced relatively to each other in the longitudinal direction of the arch, a broken bonding brace connecting said brace polygons at a point above their point of intersection, secondary braces connecting the breaking points of said brace polygons with the arch, and a vertical brace connecting the breaking point of said bonding brace with the arch.
20. In a structural system comprising an arch having a concave breaking point and a tie member, a strut connected to the breaking point of the arch and to said tie member, at least two brace polygons, each consisting of a broken arch of braces, provided between the arch and the tie member in each half of the span of the arch, the top points of said brace polygons being displaced relatively to each other in the longitudinal direction of the arch, a broken bonding brace connecting said brace polygons at a point above their point of intersection, secondary braces connecting the breaking points of said brace polygons with the arch, and a vertical brace connecting the breaking point of said bonding brace with the arch.
21. In a structural system comprising an arch having a concave breaking point and a tie member, a strut connected to the breaking point of the arch and to said tie member, at least one pair of brace polygons, each brace polygon consisting of a broken arch of braces, provided between the arch and the tie member in each half of the span of the arch, the top points of the brace polygons in each pair being displaced relatively to each other in the longitudinal direction of the arch, a bonding brace connecting said brace polygons of each pair at a point above their point of intersection, an additional, obliquely positioned brace in each half of the arch extending between the breaking point of the arch and the end thereof, the ends of the bonding braces located towards the center of the arch being located on said additional braces, and secondary braces connecting the breaking points of said brace polygons with the arch.
22. A method in the construction of a structure having an arch, a tie member for said arch, and braces connecting the arch and the tie member, comprising arranging the arch, the tie member and the braces in their places, subjecting the tie member and the braces to initial tensile stresses, thereby imparting stresses to the arch, and definitely securing the tie member and the braces to one another and to the arch while maintaining said initial stresses.
23. A method in the construction of a struc-

ture having an arch, a tie member for said arch, and braces connecting the arch and the tie member, comprising arranging the arch, the tie member and the braces in their places, subjecting the tie member and the braces to initial tensile stresses of such magnitude that the arch is

made practically free from moments, and definitely securing the tie member and the braces to one another and to the arch while maintaining said initial stresses.

ERIK JOHAN VON HEIDENSTAM.
